United States Patent Office

Des. 178,833
Patented Sept. 25, 1956

178,833

LADY'S HAT OR SIMILAR ARTICLE

Irene Greene, New York, N. Y.

Application January 3, 1956, Serial No. 39,550

Term of patent 14 years

(Cl. D3—13)

Fig. 1

Fig. 2

Fig. 1 is a front perspective view of a lady's hat showing my new design; and

Fig. 2 is a rear perspective thereof.

I claim:

The ornamental design for a lady's hat or similar article, substantially as shown.
